UNITED STATES PATENT OFFICE.

FREDERICK S. CHASE, OF WATERBURY, CONNECTICUT.

DESIGN FOR A SHADE-HOLDER.

SPECIFICATION forming part of Design No. 26,105, dated September 29, 1896.

Application filed August 3, 1896. Serial No. 601,563. Term of patent 7 years.

To all whom it may concern:

Be it known that I, FREDERICK S. CHASE, of Waterbury, in the county of New Haven and State of Connecticut, have invented a new Design for Shade-Holders for Incandescent Electric Lamps; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation; Fig. 2, a reverse plan view.

15 My invention relates to a design for shade-holders for incandescent electric lamps; and the design consists in the configuration and ornamentation as herein shown and described.

20 My newly-designed holder comprises a shade-ring A, having three rounded ears B B B projecting from its edge and arranged equidistant from each other. Each of these ears carries a retaining-screw C, each having the

outer face of its head ornamented by a rosette C'. The clamping-ring D of the device is smaller than the shade-ring and located concentrically within the same, with which it is formed integral and with which it is connected by means of webs E and E', the web 25 E being ornamented by oppositely-extending scroll-shaped corrugations e e, while the web E' is ornamented with small scroll-like corrugations e' e'. The fixed end of the clamping-ring D merges into the web E', while its 30 free end D' is furnished with a clamping-screw F, which enters a lug F', extending upward from the web E'.

I claim—

The design for a shade-holder for incandescent lamps, as herein shown and described.

In testimony whereof I have signed this specification in the presence of two subscribing witnesses.

FREDERICK S. CHASE.
